CAN COVER

William Albert Rathbun and Frank Joseph
Doyle, Grand Rapids, Mich.

Application March 9, 1934, Serial No. 714,849

4 Claims. (Cl. 220—66)

The present invention relates to a cover for a can or the like and has for its prime object to provide a cover having incorporated therein means to facilitate pouring the contents from the can.

5 A further important object of the invention resides in the provision of a can cover of this nature which is simple in its construction, inexpensive to manufacture, thoroughly efficient and reliable in use and otherwise well adapted to the purpose for which it is designed.

10 With the above and numerous other objects in view as will appear as the description proceeds, the invention consists in certain novel features of construction, and in the combination and arrangement of parts as will hereinafter be more fully described and claimed.

In the drawings:

Figure 1 is a vertical section through the upper portion of a can and our improved cover mounted thereon.

Figure 2 is a top plan view of the cover.

Figure 3 is a detail section taken substantially on the line 3—3 of Figure 1.

Figure 4 is a view similar to Figure 1 showing the cap removed and the can tilted.

Figure 5 is a top plan view of the cover with the cap removed, and

Figure 6 is a detail section through a portion of the cover showing the snap on cap in place.

30 Referring to the drawings in detail it will be seen that numeral 5 denotes a can. Numeral 6 denotes the disk like body of the cover provided with a peripheral flange 7 of a somewhat inverted U-shape or channel formation as shown clearly in Figure 1 so as to fit over the upper edge of the can 5. The disk like body 6 is formed with a trough 8 extending diametrically across the body from one side to adjacent the other side and adjacent said other side merging into a circular well

40 9, the bottom of the trough 8 inclining downwardly toward the bottom of the well as clearly shown in Figure 1. This well 9 has its bottom at the center formed with an opening 10 from which rises an annular flange 11 curved over and outwardly and downwardly. A snap on cap 12 is engageable with the flange by having a flange 14 to fit over the flange 11 and terminating in the fluted fringe portion 15. When the cap 12 is removed the can may be tilted so that the contents flowing

50 through the opening 10 will flow down through the trough 8.

It is thought that the construction, utility and

advantages of this invention will now be clearly understood by those skilled in this art without a more detailed description thereof.

Changes in the details of construction may be resorted to without departing from the spirit or scope of the invention as hereinafter claimed.

Having thus described our invention, what we claim as new is:

1. A cover for a can or the like comprising a disk like body formed with a trough extending from one edge to a point spaced therefrom and merging into a well, the bottom of the trough inclining downwardly to the bottom of the well, said bottom of the well being provided with an opening, and cap means associated with said opening.

2. A cover for a can or the like comprising a disk like body formed with a trough extending from one edge to a point spaced therefrom and merging into a well, the bottom of the trough inclining downwardly to the bottom of the well, said bottom of the well being provided with an opening, and cap means associated with said opening, an annular flange rising from the bottom of the well around the opening and being curved upwardly outwardly and downwardly, and said cap having a flange to snap thereover.

3. A cover for a can or the like comprising a disk like body formed with a trough extending from one edge to a point spaced therefrom and merging into a well, the bottom of the trough inclining downwardly to the bottom of the well, said bottom of the well being provided with an opening, and cap means associated with said opening, an annular flange rising from the bottom of the well around the opening and being curved upwardly outwardly and downwardly, and said cap having a flange to snap thereover, a channeled flange formed about the periphery of the body.

4. A cover for a can or the like comprising a disk-like body formed with a trough extending from one edge to a point spaced therefrom and being of equal width throughout its length and merging into a well, the diameter of which is greater than said width, the bottom of the trough inclining downwardly to the bottom of the well, said bottom of the well being provided with an opening, and cap means associated with said opening.
